H. Y. ARMSTRONG

ENVELOPE

Filed Feb. 11, 1918

Inventor
Harry Y. Armstrong
By William L. Steer
Atty.

UNITED STATES PATENT OFFICE.

HARRY Y. ARMSTRONG, OF SPRINGFIELD, MASSACHUSETTS, ASSIGNOR OF ONE-HALF
TO WILLIAM L. HALL, OF CHICAGO, ILLINOIS.

ENVELOPE.

Application filed February 11, 1918. Serial No. 216,445.

To all whom it may concern:

Be it known that I, HARRY Y. ARMSTRONG, a citizen of the United States, and a resident of Springfield, in the county of 5 Hampden and State of Massachusetts, have invented certain new and useful Improvements in Envelopes; and I do hereby declare that the following is a full, clear, and exact description thereof, reference being 10 had to the accompanying drawings, and to the characters of reference marked thereon, which form a part of this specification.

This invention relates to a novel envelope, and the purpose of the invention is to produce 15 an envelope of a form in which the blank, subsequently folded and pasted to produce the envelope, may be cut from a web or strip of paper without waste and subsequently folded to produce paste flaps 20 which are gummed to close the envelope without removing or cutting any portion of the material from the blank.

A further object of the invention is to produce 25 an envelope of this character with a minimum amount of material.

Another object of the invention is to produce an envelope, the blanks of which may be cut from a web of paper or like material as it is unwound from a roll; and the folding 30 and pasting operations to complete the envelope may be effected either by hand or suitable automatic machinery.

The invention consists in the combination 35 and arrangement of the parts shown in the drawings and described in the specification, and is pointed out in the claims.

In the drawings,

Figure 1 illustrates a web of paper, as it is unwound from a paper roll, showing the 40 manner of severing the envelope blanks therefrom.

Figure 2 is an enlarged view of one of the blanks showing the fold lines in broken outlines.

Figure 3 is a front view of the envelope 45 with the front and rear walls folded flat together and the closing flap extended therefrom.

Figure 4 is a section on the line 4—4 of 50 Figure 3.

Figure 5 illustrates the partially folded envelope with the paste flaps folded in their closing positions.

Figure 6 is a cross section on the line 6—6 55 of Figure 5.

Figure 7 is a front face view of the completed envelope, with the closing flap inserted therein.

Figure 8 is a cross section on the line 8—8 of Figure 7.

As shown in Figure 1, 10 designates a web of paper or like material, which is unwound from a roll 11. The web is transversely severed along lines 12 to produce the separate blanks 13 outlined in Figure 1, 65 and shown in Figure 2, the severance lines extending entirely across the web. Adjacent severance lines are disposed at oblique angles to each other to produce blanks, each of which is wider at one end than the other. 70 The blanks may be severed by the use of knives 14 illustrated in Figure 1, the angle of presentation of which, to a line extending longitudinally through the web, is alternately changed as the knife is presented 75 to the web to cut the blanks therefrom in the manner indicated in the full and dotted outline of the knife 14 in Figure 1.

After the blanks are cut from the web they are transversely scored along the lines 80 15 and 16, the line 15 dividing the rear wall 17 of the envelope from the front wall 18 thereof, and the line 16 dividing said front wall 18 from a terminal closing flap 19, which closing flap is located at the narrower end of the blank. The blank is also scored along longitudinally extending lines 85 20—20 at the sides thereof, which score lines are parallel to each other and lie inside the adjacent oblique edges of the blank to produce tapered side paste flaps 21 and 22, associated respectively with the rear and front walls 17 and 18 of the envelope. Said fold lines 20 extend from the extreme end of the wider portion of the blank to the intersection 90 of the fold line 16 with the side margins of the blank.

When the blank has thus been scored the rear wall 17 is folded flat against the front wall 18 of the envelope in the manner indicated in Figures 3 and 4; the paste flaps 21 and 22 at this time extending laterally beyond the edges of said walls. Said paste flaps which have previously been gummed are thereafter folded over the wall 18 of the 100 envelope and pasted thereto. Paste is applied to the rear side of the paste flaps 21 throughout their length and is applied to the opposite or front side of the flaps 22, as seen in Figure 2. When said flaps 21 and 110

22, with paste applied thereto, are thereafter folded upon each other and over the wall 18 of the envelope, the smaller flaps 22 are pasted directly to said front wall, and 5 the wider flaps 21 are folded over the narrower flaps 22 and are pasted thereto in the parts thereof which overlie the narrower flaps and are also pasted to the wall 18 of the envelope in the parts of the flaps 21 10 which project inwardly beyond the pointed parts of the narrower flaps. This relation of the wider and narrower paste flaps 21 and 22 is clearly shown in Figure 6.

The closing flap 19 is adapted to be inserted into the envelope over the contents designated as 23 in Figure 8. By reason of the length of closing flap 19 herein shown, it becomes practicable to use the envelope for second class mail matter, the long flap folded 20 into the envelope over the contents thereof effectively closing the envelope while at the same time permitting the contents to be readily inspected.

It will be apparent that the design of the 25 construction shown is such as to produce a strong and durable envelope which may be made with a minimum quantity of paper and without waste.

It will be observed by reference to Figures 6 and 7 that the overlying flaps 21, 22, 30 pasted to one wall of the envelope and pasted one flap to the other, produces an exceedingly strong joint or connection between the walls, and with the use of a small 35 amount of stock. These envelopes are well adapted to be made in large sizes for carrying merchandise and bulky second class mail matter and the reliable connections between the ends of the envelope walls is of considerable importance. A further advantage 40 of making the blanks with continuous tapered edges is that said edges can be cut by a very simple cutting device, illustrated in full and dotted lines in Figure 1.

45 I claim as my invention:

1. An envelope blank wider at one end than the other and uniformly tapered at its 50 side edges, transverse score lines to produce front and rear wall sections and a terminal closing flap section, the latter at the narrow end of the blank, and longitudinal score lines at the sides of the blank parallel to each other and lying inwardly from and at oblique angles relatively to said side edges 55 to produce tapered paste flap sections at the ends of both front and rear wall sections, said longitudinal score lines terminating at the transverse score line which divides the closing flap section from the adjacent wall 60 section.

2. An envelope blank wider at one end than the other and uniformly tapered at its side edges, transverse score lines to produce front and rear wall sections and a terminal closing flap section, the latter at the narrow 65 end of the blank, and longitudinal score lines at the sides of the blank parallel to each other and lying inwardly from and at oblique angles relatively to said side edges to produce tapered paste flap sections at the 70 ends of both front and rear wall sections, said longitudinal score lines terminating at the transverse score line, which divides the closing flap section from the adjacent wall section, there being paste applied throughout the length of the tapered flap sections of each wall section, with the paste on one of the pair of flap sections of one wall section at the side of the blank remote from the paste applied to the other pair of flap sections. 75

3. An envelope blank wider at one end than the other and uniformly tapered at its side edges, transverse score lines to produce front and rear wall sections, and a terminal 85 closing flap section of a width at least as great as half the width of a wall section, and at the narrower end of the blank, said blank being also provided within its tapered margins with score lines parallel to each other to produce tapered flaps, the wider portions 90 of which are at the wider end of the blank and the narrower portions of which terminate at points at the junctions therewith of the score line which divides the closing flap 95 section from the adjacent wall section, the portions of the tapered flaps abreast the front and rear wall sections, respectively, bearing paste throughout their length, with the paste of the flap sections of the two walls, 100 respectively, on opposite sides of the blank.

4. An envelope comprising rectangular front and rear non scored walls of equal dimensions and a freely operable closing flap, 105 said front and rear walls being each provided at their ends with tapered paste flaps, one of which is narrower than, and constitutes a symmetrical extension of, the other, and which are interfolded to lie one over the other and both over one wall, with the 110 wider ends of said flaps overlying and pasted to the parts of the narrower flaps and to one of said walls, said flaps bearing paste throughout their length on respectively opposite sides thereof. 115

In testimony whereof I claim the foregoing as my invention, I hereunto append my signature at Springfield, Massachusetts, this 6th day of February, 1918.

HARRY Y. ARMSTRONG.
